UNITED STATES PATENT OFFICE.

CHARLES RICHARD HAMLIN, OF CHICAGO, ILLINOIS.

DISPLAY STAND.

Application filed August 30, 1926. Serial No. 132,578.

This invention relates to display stands for supporting and displaying various articles of merchandise and the general object of the invention is to provide a display stand 5 which may be employed to display merchandise to the best advantage.

Another object of the invention is to provide a display stand which may be readily adjusted so that the support for the merchandise to be displayed may be positioned at any desired angle of inclination, and in this connection the invention also has as its 10 object to provide a stand, the component members of which may be variously relatively arranged so as to provide for conversion of the stand from one form to another in a few moments time and to enable the stand to be employed to the best advantage in supporting and displaying different 15 types of articles of merchandise.

Another object of the invention is to so construct the stand that when the component parts thereof are properly arranged and adjusted there will be no possibility of collapse of the stand as is frequently the case 20 in the use of stands which have heretofore been employed.

Another object of the invention is to provide a display stand so constructed that a 25 number of supporting sections may be assembled with the upright or standard of the stand, thus increasing or decreasing the capacity of the stand as may be desired and in accordance with the character and quantity 30 of merchandise to be displayed.

Another object of the invention is to provide an extremely simple locking means for securely connecting the component parts of the stand to one another when they have 35 been properly relatively arranged, the construction of the locking means being such that the component parts of the stand cannot become relatively displaced through accident or through handling of the stand but must be bodily adjusted to effect their relative separation and in a manner which would not ensue through any disturbance or handling of the stand under ordinary conditions of use.

Another object of the invention is to so 40 construct the stand that it will be adapted to support not only articles of merchandise but also advertising or display cards, so that attractive displays may be arranged.

In the accompanying drawings:

Figure 1 is a perspective view illustrating one form of stand embodying the invention, the component parts thereof being arranged in one of the many possible ways to support articles of merchandise. 60

Figure 2 is a detail vertical sectional view taken substantially on the line 2—2 of Figure 1, looking in the direction indicated by the arrows, and illustrating the manner in which the upright of the stand is assembled 65 and locked with respect to the base of the stand.

Figure 3 is a view similar to Figure 2, but illustrating the parts relatively separated. 70

Figure 4 is a detail vertical sectional view taken substantially on the line 4—4 of Figure 1, looking in the direction indicated by the arrows, and illustrating the means provided for locking the brace of the stand to 75 the base thereof.

Figure 5 is a detail vertical sectional view taken substantially on the line 5—5 of Figure 1, looking in the direction indicated by the arrows, and illustrating the manner in 80 which an auxiliary upright section is assembled with the main upright section of the stand and supported thereby, the view illustrating in dotted lines, the manner in which the parts may be relatively separated. 85

Figure 6 is a fragmentary side elevation of the upper end of a modified form of auxiliary upright.

Figure 7 is a side elevation of a stand embodying the base, the upright, and the brace 90 illustrated in Figure 1, but with these parts arranged in a manner different from that illustrated in Figure 1.

Figure 8 is a similar view illustrating another possible arrangement of the said 95 parts of the stand.

Figure 9 is a similar view illustrating the manner in which the component parts of the stand are arranged where a low, flat display is desirable. 100

Figure 10 is a side elevation illustrating a modification of the invention as regards the arrangement of the component parts of the stand.

Figure 11 is a similar view illustrating 105 another arrangement of the parts.

Figure 12 is a view similar to Figure 4 illustrating a modified form of brace.

Except in the arrangement illustrated in Figures 10 and 11 of the drawings, the stand 110

embodying the invention consists essentially of a base which is indicated in general by the numeral 1, an upright which is indicated in general by the numeral 2, a brace which is indicated in general by the numeral 3, and where desired, one or more auxiliary upright sections indicated in general by the numeral 4. All of the members of the stand are preferably formed of wire and each member is preferably formed of a single length of wire bent to the required shape, as will now be explained.

The base 1 of the stand is of the general form of an oblong rectangle and may be of any desired width and length depending upon the nature of the articles of merchandise to be supported and displayed upon the stand, and this base includes side members 5 and end members 6 and 7, the base being, as previously stated, formed from wire. At intervals in their length, the side members 5 of the base are formed with bends 8, the shape of which is most clearly shown in Figures 2 and 3 of the drawings, and these bends, in the position occupied by the base in Figure 1, have their open sides presented upwardly. Each bend provides a seat 9 which is of arcuate contour and of an extent somewhat greater than a half circle, and at the open upper side of this seat the opposite sides of the bend 8 are pressed or otherwise formed to provide shoulders 10 so that the said open upper side of the seat is somewhat restricted. The opposing sides of the bend, above the shoulders, form a throat 11 which is of a width preferably greater than the horizontal dimension of the seat 9. The bends in the side members 5 of the base are located opposite one another so that there is provided a series of pairs of the bends or seats and these are designed to accommodate the lower end of the upright 2 and the lower end of the brace 3 in a manner which will presently be explained. In forming the end member 6, the side members 5 are bent upwardly and thence backwardly upon themselves to provide looped extensions 12, and the wire of which the base is formed is also bent to provide the transverse end member which extends between said extensions 12. By reference to the several figures of the drawings, it will be observed that the bends which provide the extensions 12 are so formed that the end member 6 occupies substantially the same plane as the under sides of the bends 8, so that it will rest upon a surface upon which the base is disposed as will also all of the said bends 8. The extensions 12 may serve as rests against which one end of an article of merchandise to be displayed may be disposed, or they may serve a further purpose which will presently be pointed out. The end member 7 is provided by continuing one side of two end-most ones of the bends 8 in a vertical direc-

tion to provide side portions 13 between which the end member 7 extends, and these side portions and the said member 7 extend above the plane occupied by the side members 5 as do also the extensions 12, and this end member may serve, as in the instance of the extensions 12, as a rest for an article of merchandise to be supported and displayed.

The upright 2 is, as previously stated, formed from a single length of wire and comprises parallel side members 14, an end member 15, and an end member 16. The end member 15 is circular in cross section throughout its entire length except that near one of its ends it is formed with a notch 17 so that the cross sectional dimension of the member at this point is slightly less than the distance between the shoulders 10 of any one of the seats 9 provided by the bends 8 in the side members 5 of the base 1. In assembling the upright 2 with the base 1, the upright is disposed in a nearly horizontal position and the notched portion 17 of the end member 15 is fitted downwardly through the throat 11 in the bend 8 at one side of the base 1, as illustrated in Figure 3 of the drawings, whereupon this portion of the end member will enter the respective seat 9. The upright is then shifted bodily laterally until the notched portion of the end member 15 is above the corresponding seat at the other side of the base 1, whereupon the said portion of the end member is fitted downwardly into the seat as in the first described instance. The upright is then swung upwardly to a greater or less angle of inclination, and when it is so adjusted, the end member 15, being rotated in the seat 9, will have its notch 17 presented in a more or less downward direction so that at this time the end member is so engaged in the seat that it cannot be removed therefrom by upward displacement of the upright or any other displacement thereof, except by again swinging the upright to its lowered position and reversing the operation just described. At this time, the notched portion of the end member 15 of the upright will occupy the position shown in Figure 2 of the drawings. It will be evident that the end member 15 of the upright may be, in the manner stated, seated in any pair of the seats 9 so that the upright may be positioned at any desired point in the length of the base and, of course, several uprights may be employed, provided the base is formed of sufficient length.

The side members 14 of the upright 2 are formed intermediate their ends with bends providing eyes 18, and the brace 3 comprises side members 19 which have their upper ends turned inwardly at right angles to provide pintles 20 which are pivotally engaged in said eyes 18, so that in this manner the brace is connected with the upright for angular adjustment with respect thereto. The brace

further includes a cross member 21 which extends between the lower ends of the side members 19 and which is engageable selectively in the pairs of seats in the side members of the base. The wire of which the brace 3 is formed is of a diameter slightly less than the distance between the shoulders 10 of the seats 9 so that the end portions of the cross piece 21 of the brace may be freely engaged in the said seat. However, it is desirable to prevent accidental disengagement of the said cross piece 21 from the seat and with this object in view, a locking sleeve 22 is slidably fitted upon the said cross piece and movable into and out of position engaging in one or the other of the seats in which the cross piece is disposed, the said sleeve being exteriorly of a diameter equal substantially to the diameter of the seat 9 and of greater diameter than the restricted upper side of the seat, the engagement of the sleeve preventing disengagement of the said cross piece from the seats, as clearly shown in Figure 4 of the drawings. At this point it will be understood that by sliding the sleeve 22 out of engagement in one or the other of the seats in which the cross piece is disposed, the cross piece may be selectively engaged in other pairs of seats so as to vary the angle of inclination of the upright 2, and then returned to its locking position. It will also be evident that inasmuch as the end member 15 of the upright 2 is selectively engageable in the seats 9 of the several pairs, and the end member or cross piece 21 of the brace is similarly selectively engageable in the said seats, there are many different angles of inclination at which the upright may be disposed and firmly braced and supported and, as a consequence, articles of merchandise which are disposed against the upright may be positioned at an angle of inclination best adapted to display the same. It will also be understood that where a plate, dish, or any similar article of merchandise is to be displayed it may be disposed directly against the upright 2 or its lower portion may be disposed to rest in the throats 11 of a pair of the bends in advance of the upright and the upper portion of the article may be disposed to rest against the upright. If desired, the brace may be formed of wire corresponding in thickness to the external diameter of the sleeve 22 and having its cross piece 21 flattened from opposite sides near its ends, as shown at 21 in Figure 12, so that the brace may be releasably engaged with the base in the same manner as the cross piece 15 of the upright 2 is attached to the base.

In order that the auxiliary upright section or support may be supported by the upper end of the upright 2, the side members 14 of the said upright 2 are bent rearwardly upon themselves, as at 23, so as to provide closed eyes 24, and they are likewise formed with bends 25 defining open seats 26, the open ends of the seats being presented upwardly and the seats being located between the bends 23 and the ends of the end member 16 of the said upright. The said auxiliary upright or support section is, as previously stated, formed of wire, and comprises side members 27 which are formed with bends 28 located opposite each other, so that when the section is properly assembled with the upright 2, portions of the sides 27 will extend horizontally and the rear portions of the sides will extend either vertically or at an angle of inclination. The said section 4 further comprises an end member 29 connecting the upper ends of the last mentioned portions of the sides 27, and an end member 30 connecting the forward ends of the first mentioned portions of the said sides 27. A cross piece 31 is arranged parallel to the end member 30 and has its ends welded or otherwise united to the upper sides of the first mentioned portions of the side members 27.

In assembling the auxiliary upright or support section 4 with the upright 2, the said section 4 is disposed in substantially the forwardly and upwardly inclined position illustrated in dotted lines in Figure 5 of the drawings, and with the end member 16 of the upright engaging between the end member 30 and cross piece 31 of the section 4. The section 4 is then moved bodily downwardly until the cross piece 31 engages in the bottom of the seat 26, whereupon the section is then swung rearwardly until the ends of the end member 31 thereof abut against the under sides of the bends 25 and against the rear sides of the side members 14 of the upright, as shown in full lines in Figure 5 of the drawings. In this manner, the section 4 is supported in the position shown in Figure 1, and in this position, articles may be disposed thereon for the purpose of display.

In the embodiment shown in Figure 1, the side members 27 of the auxiliary upright section 4, at the upper ends of their rear portions, extend on straight lines to their juncture with the ends of the end members 29, but as illustrated in Figure 6 of the drawings, these sides 27 may be formed each with a bend 32 corresponding to the bends 23 in the side members 14 of the upright 2, and with other bends 33 corresponding to the bends 25 and provided seats 34 corresponding to the seats 26, so that where the sections 4 are thus formed, one section may be adapted to another, and so on, and thus the capacity of the stand may be increased as desired.

In Figures 7, 8 and 9 of the drawings, parts corresponding to parts illustrated in the previously described figures, namely, Figures 1 to 5 inclusive, are indicated by corresponding reference numerals inasmuch as the construction of the parts does not

125

130

vary, these views merely illustrating different possible arrangements of the component parts of the stands.

In Figure 7 of the drawings, the parts constituting the base, the upright, and the brace, are relatively assembled and arranged in quite a different manner from the arrangement shown in Figure 1, for in this arrangement the extensions 12 of the base 10 constitute seats upon which the lower end of the base is supported when the stand is disposed upon a supporting surface, the base in this instance being disposed in an inclined position and serving as a rest or support for 15 one or more articles of merchandise and thus performing the function previously performed by the upright 2 in the previously described embodiment. Likewise, in this arrangement, the member 2 has its end 15 20 engaged interchangeably in pairs of the seats 9, but instead of being disposed in an upright position or upwardly inclined position with relation to the member 1, it is inclined downwardly and rearwardly and the bends 25 23 in its side members 14 rest upon the surface upon which the stand is disposed. Likewise, the brace 3 has its end 21 engaged interchangeably in the seats 9 so that the member 1 may be disposed at various angles of inclination, the pintles 20 upon the side members 30 of the said member 3 remaining pivotally engaged in the eyes 18 of the member 2.

Figure 8 illustrates an arrangement somewhat similar to that shown in Figure 7 except that in this arrangement of the component parts of the stand, the member 1 is reversed end for end and likewise turned over, the end members 15 and 21 of the members 2 and 3, however, being still selectively or interchangeably engageable in the seats 9 in the side members of the said member 1. In this embodiment, the sides 13 and cross piece 7 of the member 1 constitute a rest for an article of merchandise disposed upon the forwardly presented side of the said member 1.

In the embodiment shown in Figure 9, the base is arranged in precisely the same manner as in Figure 1, and the upright 2 is assembled with the base in the same manner as in Figure 1. However, in this embodiment, it is desirable that the upright 2 be disposed more clearly flatwise than in Figure 1, and this is accomplished in a manner which will now be explained. In this arrangement, the end member 15 of the upright 2 is engaged in the seats 9 of the side members of the base in the manner previously explained and, likewise, the lower end of the brace 3 is engaged in a pair of the seats, but for the purpose stated, the pintles at the lower ends of the brace 3 are engaged in the eyes 24 rather than in the eyes 18.

Returning to a consideration of Figure 1 65 of the drawings, it will be observed that the

base 1 is adapted to accommodate and support another type of upright which is indicated in general in the said figure by the numeral 35, and which upright is designed chiefly for supporting pieces of chinaware in upright position, although it may support other articles of merchandise. This upright is formed in part of wire bent to provide side members 36 which are parallel to each other and an end member 37 provided with a notch 38, the said end member and notch corresponding respectively to the end member 15 and notch 17 of the upright 2. The side members 36 may be reenforced with respect to the end member 37 by reverse bends 39 and 40 formed between the lower ends of the side members and the outer ends of the end member. These bends, and more particularly the bends 40, serve another purpose, namely, that when the ends of the end member 37 are seated in opposite ones of the seats 9, the bends will engage against the outer sides of the shoulders 10 in addition to the engagement of the upper side of the end portions of the end member 37 with the said shoulders. The base as well as the other component parts of the stand are formed preferably of resilient wire and by reference to Figure 1, it will be observed that the notch 38 is located somewhat inwardly of the adjacent end of the member 37 so that in separating the upright 35 from the base, that side 5 of the base next adjacent which the notch 38 is located, is sprung inwardly until the notch is in position within the corresponding seat 9 whereupon this end of the said member 37 may be disengaged from the seat and the member 37 then slid longitudinally through the other seat until the notch 38 is positioned therein, and the upright may then be bodily lifted out of engagement with the base, it being unnecessary in such a construction, to swing the upright downwardly to effect engagement of the notched portion of its member 37 in the seat 9 as in the case of the upright 2. The numeral 41 indicates a sheet metal rest which extends between the upper ends of the side members 36 and is preferably rolled to provide sleeve portions 42 at its said ends engaging said upper ends of the side members, and this constitutes a rest against which the article of merchandise may be disposed.

By reference to Figure 10 of the drawings, it will be observed that a plurality of the uprights 35 may be arranged at intervals in the length of the base 1 and that the base in this embodiment is identical with the base shown in the previously described figures of the drawings.

As will be evident by reference to Figure 11 of the drawings, the members 35 may serve another purpose, namely that of supporting one end of the base in elevated position.

tion while the other end is disposed to rest upon the surface upon which the stand is to be supported, this being accomplished by frictionally fitting the ends of the cross piece 41 into the bends 12 of the base, as shown in

70

the said figure, the cross piece 37 of the member 35, in this instance, resting upon the surface upon which the stand is disposed.

75

It will be evident that while the purpose 10 of the seats 26 is to accommodate the cross piece 31 of the auxiliary upright or support 4, the lower margin of an advertising or display card may be disposed in these seats and thus supported at the top of the upright 15 2, when the said auxiliary upright section 4 is not employed.

80

While several arrangements of the component parts of the stand have been illustrated in the drawings, there are, of course, 20 many other ways in which the said parts may be arranged so as to support articles of merchandise of various kinds in various positions.

85

It will be evident, with reference to the 25 embodiment of the invention shown in Figure 10 of the drawings, that the uprights 35 may be arranged in suitably spaced relation to one another upon the base member 1, so as to accommodate between them a plurality 30 of articles of merchandise, or the uprights may be arranged one at each end of the frame and a stack of articles of merchandise disposed between the said uprights and resting upon the base 1.

90

35 Likewise, it will be understood that any suitable advertising matter may be displayed upon the surfaces of the cross pieces 41 of the uprights 35 and either applied directly to the surface thereof or supported 40 upon the surface by any conventional means.

95

Having thus described the invention, what I claim is:

100

1. A display stand comprising a base including side members having opposed seats 45 therein having restricted open sides, an article supporting upright including a cross piece of cross sectional diameter to fit within and substantially fill the seats and having a portion adjacent one end of reduced diameter whereby the cross piece may be freely introduced into a seat of one of the side members through the restricted open sides thereof and slid longitudinally through the said seat and introduced into a seat of the 55 other side member.

105

2. A display stand comprising a base including side members having opposed seats therein having restricted open sides, an article supporting upright including a cross 60 piece of cross sectional diameter to fit within and substantially fill the seats and having a portion of reduced diameter to adapt the cross piece to be freely introduced into the seats through the restricted open sides thereof, a brace extending between the said up-

110

right and the base and having a cross piece engageable in other ones of the opposed seats, and means slidably mounted upon the said cross piece of the brace to releasably lock the same in the seats.

115

3. A display stand comprising a base including side members movable toward and away from each other and having opposed seats therein having restricted open sides, the said seats being of arcuate contour and of angular extent greater than a half circle whereby to have restricted open sides, and an article-supporting upright including a cross piece circular in cross section and of a diameter substantially equal to the diameter of the seats and engaged within and substantially fill the seats, the said cross piece having a portion adjacent one end of reduced diameter to adapt the same to be introduced into the seats through the restricted open sides thereof and the distance between the said reduced portion and the other end of the cross piece being less than the normal distance between the side members of the base.

120

4. A display stand comprising a base including side members having opposed seats therein having restricted open sides, an article-supporting upright including a cross piece of cross sectional diameter to fit within and substantially fill the seats, the said cross piece having a notch formed therein whereby to adapt it to be fitted into the seats through the restricted open sides thereof, and a brace extending between the said upright and the base.

125

5. A display stand comprising a base including side members having opposed seats therein having restricted open sides, a supporting member including a cross piece of cross sectional diameter to fit within the seats, and a locking element slidably arranged upon the cross piece and adjustable thereon to engage within one of the seats and exteriorly of a diameter greater than the restricted open side of the seat whereby to lock the cross piece within the seat.

130

6. A display stand comprising a base including side members having opposed seats therein having restricted open sides, a supporting member including a cross piece of cross sectional diameter to fit within the seats, and a sleeve slidably arranged upon the cross piece and adjustable thereon to engage within one of the seats and exteriorly of a diameter greater than the restricted open side of the seat whereby to lock the cross piece within the seat.

135

7. A display stand comprising a base including side members having opposed seats therein having restricted open sides, the said side members being resilient whereby they may be relatively displaced toward each other against their resiliency, and a supporting member including upright side portions

140

and a cross piece, the cross piece being of a cross sectional diameter to fit within the seats and fill the same and having a portion spaced inwardly from one of the side members and of reduced diameter to adapt the cross piece to be introduced into the seats through the restricted open sides thereof, the distance between the reduced portion and the other end of the cross piece being less than the normal distance between the side members of the base.

8. In a display stand, a supporting upright including side members provided with seats having upwardly presented open sides and closed lower sides located in proximity to the said side members, and a supporting member including sides and spaced cross pieces, said supporting member being assembled with the upright with one of its said cross pieces engaging in the said seats and the other cross piece engaging against the said closed lower sides of the seats and said side members of the upright.

9. In a display stand, a supporting upright including side members provided with

seats having upwardly presented open sides and closed lower sides, and a supporting member including sides and spaced cross pieces, the said supporting member being assembled with the upright with one of its said cross pieces engaging in the said seats and the other cross piece engaging against the said closed lower sides of the seats.

10. In a display stand, a supporting upright including side members bent back adjacent their upper ends and then upwardly to provide seats having upwardly presented open sides and closed lower sides and a supporting member including side members and spaced cross pieces, extending between the side members at one end of the supporting upright, the said supporting member being assembled with the upright with one of its said cross pieces engaging in the said seats and the other cross piece engaging against the said closed lower sides of the seats and adjacent portions of the side members of the upright.

In testimony whereof I affix my signature.

CHARLES RICHARD HAMLIN. [L.S.]
